(57) **CLAIM**

The ornamental design for a barbecue implement with laminated grip, as shown and described.

DESCRIPTION

FIG. 1 is a reduced perspective view of a barbecue implement with laminated grip showing my new design;

FIG. 2 is a side elevational view illustrating one leg of the barbecue implement with laminated grip shown in FIG. 1; FIG. 3 is a front view illustrating one leg of the barbecue implement with laminated grip shown in FIG. 1; and, FIG. 4 is a bottom view illustrating one leg of the barbecue implement with laminated grip shown in FIG. 1.

The side not shown is a mirror image of the side shown, the rear elevation is identical to the front elevation shown. The top is a mirror image of the bottom shown, the broken line showings form no part of the claimed design and the leg not illustrated in FIGS. 2 3 and 4 is a mirror image of the leg as illustrated.

FIGS. 2-4 are shown separately for ease and clarity of illustration.
